UNITED STATES PATENT OFFICE.

ROBERT E. BLACKBURN, OF LOS ANGELES, CALIFORNIA.

WINDOW SCREEN.

Application filed November 8, 1922. Serial No. 599,676.

This invention includes a structure which is applicable to various kinds of frames such as the frames for the closures of windows and doors; but it is more particularly intended for use for the frames of reticulated wire screens for excluding insects from openings into buildings, and it is applicable to what are known as full screens and also to half screens; and to suspended, sliding, hinged, and stationary screens. Its description and illustration as a suspended screen will be sufficient for the purposes of this specification.

Various objections obtain in the use of ordinary wooden frame wire window screens. Amongst such objections may be noted the following:

First. The lateral tension of the wire cloth or web tends to bow the stiles of the screen frame toward each other and pressure upon the middle of the web is likely to cause the web to become loose and bellied.

Second. The wooden stiles are likely to bow out from flat form, thus leaving cracks between the screen stiles and the frame to which they are fitted, when the screen is fastened to the frame of the screened opening only at the top and bottom.

Third. The joints of the four corners of the screen frame are likely to be frail and easily loosened.

Objects of this invention are to provide a screen which is free from any of the foregoing objections, and this I do by providing a combination of wood and metal; and in carrying out this invention, I provide two rabbeted rails, each having a saw kerf at each of its ends, and I connect these rails by resilient metal stile strips of appropriate length by inserting the ends of such strips in the saw kerfs and securing them by screws in the wooden rails, and fastening to each of such floating strips, wooden stile moldings and rail spacers, the faces of which are flush with the faces of the rabbets on the rails, so that faces of such rabbets and moldings lie in a common plane and form nailings faces to which the web or wire screen cloth may be tacked; and such moldings are not rigid to the rails, but are movable edge-wise toward and from each other and may be yieldingly held apart by the resilience of the stile strips to which said moldings are fixed; and I give to the stile strips a permanent set or edgewise outward bow away

from each other as hereinafter set forth so that stile strip tension is applied to hold the web or wire mesh taut; and furthermore by the combination with the wooden moldings and the stile strips to which said moldings are fastened and the rails to which the stile strips are fastened, it is possible for the screen frame to be given a bend reverse to that which the warping action of the weather may give to the wooden stiles of the common wooden screen frame construction, so that in the case of suspended screens in which the top of the screen is fastened to the window casing, and a fastening is applied to secure the lower end of the screen to the lower end of the casing, the screen frame will lie flat and in close contact with the stops or casing of the opening to which the screen is fitted.

In carrying out this invention, I have provided a practical form of resilient metal stile strips, which are capable of being given a bow form both edgewise and flatwise that for all practical purposes with respect to the matters above set forth are permanent, that is to say, by my novel form of steel stile strip by which the floating moldings are carried, a practically permanent resiliency can be provided for a person finishing the screen at the time of hanging the screen, thus allowing the screen to be handled in knock-down form, and easily put together at a building or at the openings where they are to be installed.

In order to avoid the objections noted, and to provide a flat, straight rigid non-warpable window screen having parallel lateral edges, I provide for each screen, two complementary angle steel stile strips, each of which is longitudinally bent to form an inner stile member or facing and an angle member or edging practically at right angles thereto; and preferably said stile strips are also respectively provided with a third or flange member, at right angles to the second, that is to say, to the intermediate or angle member, and projecting away from said angle member, and forming a flange to fit against the stop or casing of the window frame.

These angle stile strips are Z-strips in that they are Z-shape in transverse section, and the invention is broadly new, basic and pioneer in that I have provided for and applied to the screen frame a Z-strip for closing

the crack between the screen frame and the frame such as the window frame in a building to which the screen is applied; and they also afford metal faces or abutments to contact with the window frame to which the screen frame may be fitted, and in the case of screens that slide up and down the middle members of the Z strips serve as smooth runners to slide on the sides of the window frame.

Said Z-strips may be made to afford the required stability for keeping the screen mesh taut; and this is done by forming the metal strips with an outward bow, securing them at their ends to the rails of the window screen; attaching to the strips respectively, moldings that are free from the rails; imposing an edgewise deflection on the strips toward each other, and opposed to the bow; fastening the edges of the screen web to the moldings and thereby to the outwardly bowed resilient strips, so that said outwardly bowed resilient strips develop a force to draw the moldings apart to keep the screen web taut.

I give the two complementary angle steel Z-strips a permanent edgewise set so that when put in place they bow slightly away from each other so that when the lateral edges of the wire cloth are fastened to the Z-strips by the fastening moldings and rail spacing members as hereinafter set forth, and is drawn taut, with the lateral edges of the Z-strips straight and parallel with each other, and the ends of the Z-strips are fastened to the rails, the stiles formed by said strips and moldings will hold the cloth taut and will resist the tension of the wire web to bow the stiles toward each other.

I also provide the top and bottom rails with rabbets on one side at their adjacent edges, and said rails are slotted in the ends by saw kerfs extending flush with the rabbets and from edge to edge of each rail, and I provide floating rail spacers or stile moldings flush with said rabbets and with the ends of the rails, to receive the flat wire screen cloth, and I fasten said cloth, preferably by tacks, to the flush faces of the rabbets and the floating moldings.

I then apply the angle steel Z strips with the ends of their inner members inserted into the kerfs and with the flat faces of such members on the faces of the rabbets, with the moldings flat against said flat faces and with the angle member outside the moldings and against the ends of the rails.

I then apply pressure to the inside of each molding and to the outside of the adjacent angle member of the curved steel Z strips, thereby drawing them into close longitudinal contact; and then fix them securely together by screws.

In drawing the angle members of the curved steel Z strips into contact with the out-

er edges of the parallel moldings, the curved steel Z strips are rendered straight and parallel. But in thus rendering the curved steel Z strips straight and parallel, there is developed in them a lateral outward stress sufficient to hold the wire cloth taut without any bowing of the stiles edgewise toward each other.

Next I apply, over the wire cloth tacked on the rabbets of the rails, and over the inner member of the angle steel Z strips, wooden fillets; and I braid each fillet to its rabbet. Then a hole is drilled into each corner of the frame and through the inner members of the angle steel Z strips, and screws are inserted in said holes, thus completing the screen.

An object is to provide a screen having metallic stiles that can be easily and cheaply manufactured in quantities, and that are adapted to receive the floating wooden moldings and resiliently hold them in true position.

A further object is to provide for suspended window screens a frame structure that will be complete in itself and ready to hang without any hardware additional to the fixture fastened on the window frame.

A further object is to so construct the screen that it can be used interchangeably for swinging and for sliding screens.

The invention is broadly new, basic and pioneer in that the frame is constructed with a sheet metal Z-strip stile with a flange extension and has a wooden molding; said stile and flange being preferably, relatively offset, and formed with a double angle to give it greater rigidity.

An important object is to give perfect rigidity to the joints of the screen; and to effect this, the jaws formed at the ends of the rails by the saw kerfs, fit the inner members of the stiles tightly and seat them fully so that the angle member may be fitted tightly against the square ends of the rails; and so that when screws are screwed home through the jaws at one side of the wooden rails and through the metal Z-strip stiles and into the jaws on the other side of the Z-shaped stile strips, the joints are firm, rigid and true, but can be easily released by taking out the screws, and then, by removing the fillets and the stile strips from over the screen cloth, such cloth can be removed and replaced with great convenience and without any injury to the frame.

Other objects, advantages and features of invention may appear from the accompanying drawing, the subjoined detail description and the appended claims.

The accompanying drawings illustrate the invention.

Figure 1 is a perspective outside view of a frame structure constructed in accordance with this invention, showing a window

screen adapted to be hung in a window frame.

Fig. 2 is a broken perspective inside view of the screen shown in Fig. 1.

Fig. 3 is a front elevation of the screen shown in Fig. 1, hung in a window frame.

Fig. 4 is an enlarged section on line x^4 , Fig. 3.

Fig. 5 is a perspective view of one of a pair of screen hangers adapted to support the screen.

Fig. 6 is an elevation of one of the sheet metal stile strips as it comes from the forming machine not shown, ready to be fastened at its ends to the frame.

Fig. 7 is a fragmental view of the inside of a screen from which the metal stile strip shown in Fig. 6 has been removed.

Fig. 8 is a fragmental cross section of the screen on line x^8 , Fig. 3.

Fig. 9 is a fragmental section on line x^9 , Fig. 3, enlarged.

Fig. 10 is an enlarged fragmental view partly in section across a stile, showing means for retaining a sliding screen in a window frame.

Fig. 11 is an edge view of a screen hinged in a frame and ready to be brought flat against the same when fastened at the bottom. The bowing of the screen stiles is exaggerated for clearness of illustration.

Fig. 12 is a fragmental face view of the screen partly assembled, with the bow of the loose stile strip exaggerated for clearness of illustration.

The double angle sheet metal Z-strip 1 is struck up from a body of sheet metal of suitable strength and resiliency comprising the stile facing 2, stile edging or offset portion 3 and the flange 4. The stile facing 2 and flange 4 in opposite directions from the edging and extend in parallel planes and are connected by the edging or offset portion 3. Each frame is built up of two double angle metallic stile strips of Z-shaped cross section that extend from end to end of the two edges of the frame; and a wooden reinforcement spacing member or molding 5 extending between the rails 6 and 7 on one side of the reticulated wire screen web 8 which is secured by any suitable means as the tacks 9 to the wire screen receiving faces 10 and 11 of the stile molding 5 and of the rails, each of which may be made of a single piece, or may be built up of more than one piece.

The stile moldings 5 are thus loose from the rails and are movable edgewise toward and from each other and are adapted to be forced apart to stretch the web 8.

Each rail is provided at each end with a slot 11 preferably formed by a saw kerf, and adapted to seat the ends of the stile facings 2, which are slipped into said slots and secured by the screws 12.

The frame of the screen is thus constructed of steel and wood. As shown in Fig. 12 the wooden parts of the screen are the top and bottom rails 6 and 7, and the two floating stile moldings 5.

While the wooden parts 6, 7 and 5 are clamped in place on an assembling table, not shown, and are thereby held in the relative positions they are to occupy in the finished screen, the web 8 of wire cloth is tacked on the rabbets or nailing faces 11' of the top and bottom rails, and then to the vertical stile moldings as indicated in Figs. 7 and 12.

The next operation is that of putting on the double angle resilient metal stile strips, which are preferably made of steel.

As they come from the forming machine, not shown, these stile strips are straight as indicated in Fig. 6. Before the resilient metal stile strips are secured to the wooden moldings of the frame, they are bent into a curved form as exaggeratedly shown in Fig. 12. Then the ends of the steel stile strips are inserted into the slots or stile seats 11, and are secured by binding screws 12.

When thus fixed in the kerfs of the rails 6, 7, the two stile strips bow away from each other as indicated by the bowed stile strip at the left side of Fig. 12, and said bowed resilient stile strips are then drawn straight into the shape indicated at the right of Fig. 12, and are brought into parallelism, and are then secured to the molding strips 5 by the screws 13 as indicated at the left side of Fig. 12, without taking out the permanent set and tendency to bow indicated at the right of Fig. 12; so that the resilient metal stile strips remain under strain and will exert a spring-like pull tending to force the moldings away from each other, thus to hold the web taut.

When the screen web 8 is nailed to the faces 10 of the stile molding 5 and to the nailing faces 11' of the rails 6, 7 to form the wire mesh panel of the screen, the metallic double angle or Z-shaped stile strips will be placed in position to cover the nailed edges of the screen material with portions of the stile ends extending into and through the kerfs 11 in the ends of rails 6, 7; and secured by means of the long binding screws 12 extending from one side of the rails, respectively, and through the facings 2 and nearly to the other side of the rails. Short screws 13 extend through the stile facings 2 into the reinforcing stile molding 5.

The screen frames can be either hung, hinged, or slidably mounted in window openings. When hung, hangers 14 are secured to the jambs 15 of the window frame by means of the screws 16, said hangers have extensions 17 that extend through the slots 18 in the upper ends of the flanges 4;

so that when hung thereon, the bottom end of the screen frame can be swung outward as indicated by the dotted line position in Fig. 4. By this mounting the screen frame for full or half screens can be quickly and easily suspended in place to close the window opening, and may be as easily removed.

Means are provided for holding the lower end of the screen frame in close contact with the inclined face *f* of the window sill; and for locking against outward movement. A lever latch 19 is pivotally mounted on the screw pin 20 in the bottom rail 7, in position to engage the lug 21 on the retaining screw 22, fixed to the sill *f*, thus to lock the screen from outward movement, and to flatten the screen under strain and to maintain it in flat form and in close contact, throughout, with the stops or jams 15.

20. The screen frames can be slidably connected to the window frame as indicated in Fig. 10, wherein, a guide strip 23 is secured to the window frame in position to engage the flange 4 to hold such flange in contact with the window frame. There is a guide strip 23 for each flange 4 and these guides are preferably of greater length than the screen frames so that the latter can have considerable upward movement in a window opening. The latch 19 can be attached to the sliding frame and locked to hold such frame in fixed position.

When the web has been nailed to the nailing faces of the rails, and to the spacing members, and the metal stile strip has been inserted into the saw kerfs and secured to the rails by the long screws 12 and to the reinforcement spacing members 5, then the finished fillets 24 are placed in the rabbet over the web and fixed to the nailing faces of the rails.

I claim:

1. In a screen the combination with edge-wise resilient stile strips having facing members and having a normal outward bow, rails holding the ends of the stile strips apart; moldings free from the rails and fixed to the facing members between the rails; and a web fastened to the molding and rails; said web holding the stile strips in tension so that the tendency of the permanent edge-wise set of the resilient stile strip is to hold the web taut.

55. A screen comprising resilient metal stile strips bowed outwardly edgewise and having a permanent set; rails fixed to the ends of the stile strips; moldings fastened to the stile strips, and free from the rails; and wire netting fixed to the rails and to the molding, and holding the stiles under tension so that the moldings are drawn apart by the stile strips, and in turn hold the netting taut.

60. A screen comprising resilient flanged stile strips, Z-shape in cross section having

a permanent set and bowed from each other; rails fastened to the faces of the stile strips to hold the ends of the stile strips apart; the flanges of said stile strips extending laterally beyond the ends of the rails; moldings 70 fixed to faces of the stile strips and free from the rails; and a sheet of screen material fixed at its edges to said moldings and holding said stile strips under tension so that the resiliency of said stile strips tends to 75 hold the screen material taut.

4. A screen having rails and stiles, moldings fixed to the stiles and movable relative to the rails, and webbing fixed to the moldings, said stiles comprising normally edge-wise bowed resilient members which are sprung into alignment upon assembling, the purpose of which is to give an outward pull on the moldings in order to keep the screen taut.

5. A screen comprising normally outwardly bowed stile members, rails holding the ends of the stile members apart, moldings fastened to the stile members and free from the rails in order that said moldings 80 may have a slight outward movement relative to the rails, and a screen panel fastened to the moldings and deflecting into alignment the normally outwardly bowed resilient stile members so that the tension of said stile 85 members serves to hold the screen panel taut.

6. In a screen having a wire mesh panel and a frame structure constructed with rails and stiles; a stile comprising a wooden member and a sheet metal member, said sheet 100 metal member being longitudinally bent to Z-shape in cross section, constituting a facing portion, an intermediate edging portion at right angles to the facing portion and a flange portion extending in a plane parallel 105 to the plane of the facing portion; said facing and flange portions extending in opposite directions from the intermediate edging portion; said intermediate edging portion being adapted to fit against the edge of the 110 wooden member of the stile; one of said facing and flange portions, being fixed flatwise to the wooden member of the stile and adapted to fit flatwise upon the casing or flange stop of a window so that the stile strip 115 forms a closure for the crack between the screen frame and the window frame.

7. A screen provided with two complementary angle steel stile strips each of which is longitudinally bent to Z-shape in cross section and forms an inner stile member or facing, an intermediate angle member or edging practically at right angles thereto, and a flange extending at right angles to the facing and in a plane parallel to the plane of 120 the stile member.

8. A screen frame comprising rails having kerfs in their ends forming jaws, and double angle metal stiles having inner members inserted in said kerfs, and edging against the 125

- ends of the rails; and a flange extending from said edging adapted to engage the outer face of a window frame casing, and screws inserted through the jaws on one side 5 of the kerfs and through the inner members and into the jaws on the other side of the kerfs.
9. A screen frame comprising rails provided with rabbets and with kerfs in their 10 ends; and stiles having edgings and inner members; said edgings fitting against the ends of the rails and said inner members extending through the kerfs and being flush with the rabbets; wooden moldings flush 15 with the rabbets and loose from the rails; wire cloth fastened on the rabbets and moldings; means fastening the wooden moldings to the inner members of the stiles with the cloth between the moldings and the stiles 20 and between the rabbets and the stiles; and screws fastening the inner members to the rails.
10. A screen frame provided with rails spaced apart by spacing members; a web 25 secured to said rails and spacing members; metallic stiles fastened to the rails and having an edgewise set so that said stiles bow away from each other, said stiles being adapted to be rendered straight and parallel 30 to develop a lateral outward stress; and means to secure said stiles to said spacing members so that said stiles will exert a lateral outward stress upon said web to hold 35 said web taut.
11. A frame structure comprising sheet metal stiles fixed to and spaced apart by rails; wooden spacing members between the rails adjacent the metal stiles and loose 40 from said rails so that they may move outwardly; a sheet of screen material secured to said rails and spacing members; and means for securing the metal stiles to the wooden spacing members and rails, whereby 45 a tension is applied to said spacing members to hold the screen taut.
12. A screen comprising a frame constructed with rails, and stiles, and a sheet of screen material secured to the stiles; one 50 of the stiles comprising a resilient sheet metal strip having a permanent edgewise outward bow to exert a pull on the screen material to keep it stretched, when said stile is resting in alignment with the rails.
13. A frame structure comprising rails; sheet metal stiles fixed to and spaced apart 55 by said rails; wooden spacing members adjacent to and parallel with the metal stiles and loose from the rails so that said rails may have a slight outward movement; a web secured to the rails and spacing members; and means attaching the metal stiles to the end rails and to the wooden spacing members with the web between the spacing members 60 and the stiles so that a tension is applied to said rails and web.
14. A frame structure comprising rails, stiles spaced apart by said rails and having a facing, a flange, and an edging connecting said facing and flange; moldings adapted to space said rails apart; a web secured to said rails and moldings; there being kerfs in the ends of said rails to receive the ends of said stiles; and means to secure said rails and moldings to said stiles.
15. The screen frame substantially set 75 forth in which the rails are wooden, and are provided with kerfs in their ends, and the stiles are of sheet metal and formed with a permanent edgewise outward set away from each other and are each provided with a facing which extends into the kerfs in the ends of the rails; screws fastening the stile facings in the kerfs; wooden reinforcing spacing members fixed to the stile facings, and abutting against the rails, and secured 80 to said facings by fastening means extending through the sheet metal facings, and into the wooden reinforcing spacing members; said rails being rabbeted to form nailing spaces to which a web may be fastened, and said reinforcing spacing members being flush 85 with the rabbet faces for the purpose of forming nailing spaces for securing the web to the spacing member; said sheet metal facings being adapted to cover the means by 90 which the web is fastened to the spacing members.
16. The screen frame substantially set 95 forth in which the rails are wooden, and are provided with kerfs in their ends, and the stiles are of sheet metal and are each provided with a facing which extends into the kerfs in the ends of the rails; screws fastening the stile facings in the kerfs; and wooden reinforcing spacing members fixed to the 100 stile facings, and abutting against the rails, and secured to said facings by fastening means extending through the sheet metal facings, and into the wooden reinforcing 105 spacing members; said rails being rabbeted to form nailing spaces to which a web may be fastened, and said reinforcing spacing members being flush with the rabbet faces for the purpose of forming nailing spaces for securing the web to the spacing member; said sheet metal facings being adapted to cover the means by which the web is fastened to the spacing members.
17. A screen provided with two complementary angle steel stile strips each of which is longitudinally bent to Z form comprising an inner stile member or facing and an angle member or edging practically at right angles thereto and a third flange member at right angles to the second, that is to say, to the intermediate or angle member, and projecting away from said angle member 110 and forming a flange to fit against the stop 115
- 120
- 125
- 130

or casing of the window frame; said edging and flange forming the lateral terminals of the stile strips.

18. In a window screen the combination 5 with a frame having in its edge a kerf extending longitudinally of the frame; a stile strip longitudinally bent to Z form comprising an inner stile member, an angle member practically at right angles to the inner stile 10 member and a flange member at right angles to the intermediate angle member and projecting away from said angle member and forming a flange to fit against the stop or casing of the window frame; said edging

and flange forming edges that terminate the 15 stile strip laterally.

19. In a window screen the combination with wooden rails and wooden side members to which the screen panel is fastened, of Z-strips fastened to the side members; flanges 20 of the Z extending edgewise from the side members for the purpose of engaging a frame in which said screen may be mounted.

In testimony whereof, I have hereunto set my hand at Los Angeles, California, this 25 31st day of October, 1922.

ROBERT E. BLACKBURN.
